COIN-CONTROLLED ACTUATOR

Wilson Marks Stewart, Ottawa, Ontario, Canada

Application September 22, 1950, Serial No. 186,135

2 Claims. (Cl. 194—61)

1

This invention relates to an actuator for vending machines.

More particularly, the invention relates to a coin-controlled release mechanism used in vending machines.

Such a mechanism, to which the present invention pertains, is used to control the rotation of a shaft which is an instrumentality in the operation of vending. Thus, such a mechanism, which normally prevents the "vending" or operative stroke of the shaft, is operated by a coin to release the shaft so that it may be freed to rotate and permit of the vending function of the machine of which the mechanism forms a part.

With the advent of the increase in the sale price of many soft drinks, from a nickel to seven cents—requiring a nickel and two one-cent pieces—such mechanism had therefore to be made adaptable to handle or receive three separate coins or money pieces. The present invention has been developed to handle a nickel (inserted into one chute) and two one-cent pieces (inserted into a second chute), but the invention is also applicable to a mechanism required to handle two or more coins inserted into a same coin chute.

Such mechanisms which handle three coins—two of which, of equal denominations, are inserted into the same coin chute—tend to function improperly.

The instrumentality directly controlled or actuated by the coin, or coins, is a latch called in the trade a "dog." One such dog is controlled by two similar coins inserted into the same coin recess or slot of the coin cam. In the operation of this dog, the two coins are co-dependent, that is, one coin actually operates the dog in its releasing stroke and this coin in turn is actuated or pushed by the other coin. The coins may be said to act in series. Experience has shown that the main cause for the improper or unreliable functioning of the known mechanisms aforesaid, is that the two coins sometimes in part overlap one another as one pushes the other to operate the dog. If one coin is thinner (because of wear or for other causes) than the other, or if both coins are worn thin, overlapping is likely to occur, and often does. The two coins therefore become wedged in the coin recess of the coin cam in which they are received after leaving the coin chute, and the mechanism will either jam, or will operate to permit vending without additional coins.

The main object of the invention is to provide an efficient and improved coin-controlled release mechanism in a so-called actuator for vending machines, particularly one of the kind wherein

2

two (or more) coins are received in a same recess of the coin cam.

A feature—the most important feature—of a mechanism according to this invention is that the first coin to be inserted into the coin recess of the coin cam receiving the two coins of equal denomination, is inoperative to actuate the dog; it is the second coin which actually operates or pushes the dog to effect its releasing stroke. The first coin merely acts partially to support the second coin. Thus, the two coins are not co-dependent in the sense that one is pushed by the other, but the second coin acts independently of the first coin to actuate the dog on its releasing stroke.

15 Better to bring out the difference between the mechanism of the present invention and that now on the market as aforesaid, a brief description will first be made of the part of the known mechanism immediately concerned with the operation of the dog—through the intermediary of two coins of equal denomination.

In the drawings, wherein like numerals of reference indicate corresponding parts in the various figures,

25 Figure 1 is a side elevation of the preferred form of the invention;

Figure 2 is a plan view of Figure 1;

Figure 3 is a view as on line 3—3 in Figure 2; and

30 Figure 4 is an isometric view of a 7-cent cam such as is now on the market.

Referring first to Figure 4, 10 shows the shaft, the rotation of which two coins (of the same denomination) and a third coin are intended to control. Through a coin chute (not shown) the two coins of the same denomination, falling successively by gravity, are guided into a coin-receiving recess or slot 27 formed in a coin cam 12 fixed to the shaft. The two coins lie in the recess, one

40 coin bearing against a pin 20 fixed to one end of a lever or dog 18, and the other coin lying adjacent one end of the recess in alignment with the other coin. The dog is spring-loaded (spring not shown) to retain the pin in riding engagement

45 with the cam. The cam is formed with a shoulder or abutment 31 adapted to be engaged by the pin 20 to determine the rotation of the shaft, when the cam is rotated against the spring (not shown) loading the shaft. The pin 26 is adapted to be raised by a coin to clear the shoulder 31.

50 In a three-coin device such as that being briefly described, two coins of the same denomination must be in the cam recess 28 before the pin 26 will be raised to clear the shoulder 31. The first coin is received in the recess and rolls down to bear adjacent the pin 26 of the dog 31. The sec-

ond coin rolls down to bear against the first coin. The dog is raised by the first coin which is pushed by the second coin, the latter coin being in turn pushed by the cam. In other words, the second coin, deriving its pushing force from the cam, pushes against the first coin as the coin cam is rotated. Thus it is that the two coins often in part overlap and become wedged in the coin slot of the cam.

The third coin (the nickel) dropped into a sec- 10 ond chute (not shown) is received into a second and parallel recess 27 and serves to lift the pin 20 of another spring-loaded dog 18. As will be easily understood, when both dogs are lifted to clear the shoulders 11, rotation of the shaft on its vending 13 stroke is possible.

My improved device is shown in Figures 1 to 3. It comprises a spring-loaded shaft 10, the rotation of which two coins D2 and D3 (of equal diameter) and a third coin D1, are intended to control. As is the case with the present-day 7-cent actuators, the shaft 10 is loaded as by a coil spring 15, wound around the shaft and anchored at its opposite ends to a lug 17 forming part of the frame F of the actuator and a pin 16 carried by the cam 12. The rotation of the cam is determined by a pin 13 carried by the coin and engaging the frame.

The coin cam 12 is provided with two parallel coin-receiving recesses or slots 27 and 28. Each such recess is formed at one end with the usual coin engaging shoulder S (see Figure 3). The two coins D2 and D3, falling through a coin chute (not shown), are received into the recess 28; the third coin D1, falling through a coin chute (not shown) is received into the recess 27.

Associated with the recesses 27 and 28 are two separate or independent spring-loaded dogs 18 and 23, respectively, pivoted to the frame as by a shaft 19, and carrying pins 20 and 26, respectively. The pins ride on the cam and normally engage shoulders or abutments 31 formed on the cam to determine the rotation of the shaft against its spring on its releasing stroke. The coin D1, in the recess 27, operates to lift the pin 20 carried by the dog 18 clear of the shoulder associated with the recess.

Thus far described, my improved device is similar in operation to that previously known, that is, the device shown in Figure 4. The difference between such known device and my improved device consists of the provision of a ramp or cam track 30 which is adapted to be slidably engaged by the pin 26 carried by the dog 23. The ramp is formed effectively to extend radially-outwardly of the effective face of the coin cam, so that in one position of the cam—its normal position (as seen in Figure 3)—the pin carried by the dog 23 is sufficiently raised to permit of the coin D3 (the first to be inserted into the recess 28) to roll in the recess, under the pin 26. The coin comes to a stop by its engagement with a plate or stop 24 fixed to the frame F of the device, the coin being in part supported by the stop and by the floor of the recess. If the coin cam is now rotated from its normal position, the pin will engage the abutment or locking shoulder and determine such rotation.

The coin D2 (the last coin to be inserted into the recess 28) is in part supported or held in a position forwardly of the pin 26 by the coin D1. The ramp is so formed that as the coin cam is partially rotated from its normal position, the pin is gradually lowered to lie in the path of the coin D2, so that the continued rota-

tion of the coin cam will cause the coin to raise the pin above or clear of the abutment 31.

Thus, the dog 23 will now be ineffective to determine the rotation of the shaft on its releasing stroke. The floor of the recesses is so formed that after the coin cam has been rotated sufficiently to render the dogs ineffective, the coins fall out of the coin recesses into a coin box (not shown).

While my improved device has been described as one handling two coins of the same denomination in a same coin recess (that is, adapted to vend 7-cent commodities), it is obvious that more than two coins of the same denomination in a same recess may be made to control the dog associated with such recess. It is merely a matter of so forming the ramp, so positioning the coin stop and so shaping the floor of the recess that the first two coins will roll under the pin, and the third coin alone will engage the pin and raise the same clear of the abutment.

What I claim is:

1. In a coin controlled actuator of the type adapted to actuate upon insertion in a single coin slot of two or more similar coins, and comprising a frame, a rotatable shaft mounted for rotation in said frame, a coin cam secured to said shaft, and a dog biased to ride on a cam track on said coin cam and limit rotation of said coin cam and shaft when correct coinage is not present in slots formed in said coin cam to receive the same, the improvement which consists in; a coin slot formed in said coin cam open to the periphery of said coin cam along its entire length and arranged to receive and hold edge to edge a predetermined number greater than one of coins fed to it by gravity from a coin chute situated thereabove; fixed stop means mounted on said frame in alignment with said coin slot and arranged to contact and support the first coin received in said coin slot whereby said predetermined number of coins are held in said coin slot after being fed thereto until actuation of said actuator moves said coin slot free of said stop; said coin slot and stop being arranged so that all save the last of said predetermined number of coins are entirely beneath said cam track; and a cut-away portion on said cam track formed with a locking shoulder at one end thereof in such position that the last coin of said predetermined number of coins to enter said coin slot projects its edge within said cutaway portion to an extent corresponding to the depth of said locking shoulder; said dog being positioned to ride said cam track within said cutaway portion to contact said locking shoulder and prevent operation of said actuator when all of said predetermined number of coins are not present in said coin slot, and to ride over the projecting edge of said last coin and past said locking shoulder to permit operation of said actuator when all of said predetermined number of coins are present within said coin slot.

2. A coin controlled actuator as defined in claim 1 in which said coin slot is designed to accommodate two coins.

WILSON M. STEWART.
